UNITED STATES PATENT OFFICE.

KARL FELIX ROHRMANN, OF ST. GALLEN, OF SWITZERLAND.

ARTIFICIAL HAND.

1,305,169.

Specification of Letters Patent. Patented May 27, 1919.

Application filed October 20, 1917. Serial No. 197,720.

To all whom it may concern:

Be it known that I, KARL FELIX ROHRMANN, a citizen of the Swiss Confederation, and residing at St. Gallen, Switzerland, 5 have invented certain new and useful Improvements in Artificial Hands, of which the following is a specification.

The present invention relates to an improved artificial hand in which the rotary 10 movement of the forearm stump is used to actuate the thumb and the rest of the fingers; and the invention essentially has for its object to provide means for independently coupling the arm stump, the 15 thumb and the four fingers in such manner that upon rotation of the stump in the one or the other direction the thumb and the fingers are simultaneously operated for closing or opening, as the case may be; the invention further enables the wearer of the 20 prosthetic hand to rotate it with all its operative parts relative to the arm stump without actuating at the same time the thumb and the fingers, so that then objects clutched 25 by the hand are held fast, no matter in which direction the stump or the hand are rotated; and lastly, the hand may be adjusted to various initial positions relative to the stump for the execution of diverse operations 30 without the first stated capability of thumb and fingers to coöperate simultaneously being suspended, as in the second instance.

My invention will best be understood 35 when described in connection with the accompanying drawing, in which Figure 1 represents a rear view of the prosthetic hand, with the cover removed to expose the interior, and partly in section; Fig. 2 shows 40 a side elevation, partly sectioned, of the hand part proper; Fig. 3 represents a side elevation of one of the fingers; Fig. 4 shows a section on line A—A of Fig. 2, Fig. 5 a side elevation of Fig. 4. Fig. 6 illustrates 45 a further fragmental side view of the hand, the shell being sectioned to expose the internal parts; Figs. 7 and 8 are cross-sections on lines B—B and C—C— respectively of Fig. 6, and Fig. 9 is a fragmentary side elevation, partly in section, of the coupling mechanism.

The upper arm bars or straps 1 extend from the brachial sleeve 2 and are pivotally connected at 3' to the forearm straps 3. To 55 the latter is fixed the wrist member 4 of inverted disk shape, the straps 3 and the

dish 4 forming the prosthetic substitute for the forearm. To the dish 4 are secured by means of rivets 5 the disks 6 and 7, of which the latter is provided with a hub or boss 8 60 within which is rotatably arranged the hub 10 of a larger hand-supporting disk 9, and the two hubs are secured against relative inadvertent displacement in longitudinal direction by the nut 11. The hub 10 freely rotates about the pivot pin 12 extending from the slightly vaulted plate 13, from the lower face of which extends the screw bolt 13^a. A yoke member 14 is pressed against this plate 13 by a nut 15 threading on the bolt 13^a, and a pin 14^a extends from the yoke and is adapted to engage in one of the bores 13^b in the plate 13, so that the yoke and the plate can be relatively adjusted in different initial positions. To the yoke member 14 is secured the forearm socket or cuff 16, adapted to be laced onto the arm stump and of varying length, depending upon the length of stump to be fitted. Above the pivot pin 12 is provided with a square portion 17 and ends in a threaded end 18, and it is held near its upper extremity in the bracket support 19 fixed to the palm interior, as clearly shown in Fig. 1. To the square portion 17 of the pin 12 are fitted the 80 toothed segment 20, the tubular spacing member 21, and the forked lever 22, the nut 23 holding the parts in position.

To the disk 9 is secured in suitable manner, for instance by screws, not shown in the 90 drawing, the hand 25 having a removable cover 24 in the back thereof.

A slightly arched spring lever 26 is secured at one end to the hand disk 9 by a screw stud 27 and a tooth 28 extending 95 downwardly from the other down-curved end of this lever passes through a corresponding aperture 9' in disk 9 and selectively coöperates with a plurality of recesses 29 in the wrist member 4 (Fig. 9). A hand 100 operable coupling lever 31 is pivotally secured by a pin 30 with its one end to the hand disk 9 and is provided near the free end extending beyond the base of the hand with a downwardly directed tooth 32, which 105 is designed to coöperate with a rack segment 33 on the disk 9 upon actuation of the coupling lever 31. A pressure spring 30^a tends to normally force this lever into its inoperative position out of coaction with the 110 rack segment 33. A dog 34 is fulcrumed on a lateral extension of the journaled end of

lever 31 and is limited in its forward movement by a stop 35 in the inoperative position of its support lever. A pressure spring 36 tends to force the dog 34 into engagement 5 with the toothed segment 20, which latter, as above stated, rotates in positive manner with the pivot pin 12. The lower end of the pin 30 extends downwardly through disk 9 into a guideway 57 provided in the superposed 10 disks 7 and 4, for limiting the rotary displacement of the hand relative to the wrist.

With the fork 22 coöperates the lever 37, which widens into a plate and is secured within the hollow hand to the root 38 of the 15 thumb 39, which latter can be turned about the pivot 40. The pin 41 on the upper extension 42 of lever 37 coöperates with the forked end 43 of the lever 44 secured to the forefinger 43, and the latter is rigidly connected to the middle finger 45, both being 20 fulcrumed on the shaft 46. The arm 47 laterally extending from the lever 37 is provided with lugs 48 into which thread the link members 49. To these latter are secured 25 the actuating members 50 for the middle joints 51, 52 of the gold finger 53 and the little finger 54, and which members are preferably in the form of tightly coiled springs suitably secured to the finger joints. 30 The parts 51 and 52 are respectively pivoted at 55 and 56 to the body of the hand, and the remaining finger joints 53 and 54 are similarly jointed to the middle joints and are similarly actuated by springs which extend 35 freely through suitable bores in the otherwise solid finger joints, as well known in the art. The fingers on their inner faces are preferably covered with rubber or similar material.

40 A draw spring 55' is secured with its one end to the inside of the hand and with its other end to a pin 56', extending from the thumb root 38 (Fig. 2).

The sleeve 2 is strapped to the upper arm 45 and the socket 16 to the forearm stump. If, as shown in the drawing the tooth 28 of lever 26 has dropped into one of the recesses 29 in the wrist member 4 and the tooth 32 is out of engagement with the rack segment 33 and 50 the arm stump is now turned, the pivot pin 12 will turn likewise in the same sense and also the members 20, 21, 22 and 23 on the pin. The lever 37, coöperating with the fork of the lever 22, will also be swung about its 55 pivot 49 with the result that the thumb as well as the fingers 43, 45 and also the fingers 53, 54 are actuated. The fingers 43 and 45, as above described, are influenced by the lever extension 42 and lever 44, and the fingers 53 and 54 by the rectangularly extending arm 47 and the draw springs 50. If the stump is rotated in the direction of the arrow *a* (Fig. 1), the hand will open up; if rotated in the sense of arrow *b*, the hand 60 will close, the thumb contacting in the end

position with the two rigidly connected first fingers 43 and 45 and the two other fingers bending over toward the ball of the thumb. Into this position the fingers can also be moved by the action of the spring 55'. Thus, 70 by rotating the arm stump in the one or the other direction the hand can be made to grasp objects and drop them again, the grasping pressure or hold being regulated by the force transmitted from the stump by 75 the pivot pin 12.

For different work manipulations different positions of the hand relative to the forearm are required. For this purpose the tooth 28 is lifted out of the respective recess 29 by operation of the lock lever 26 and the hand is then turned by the other hand into the required relative position; this, however may also be done by rotating the stump to the required extent. In the desired position, 80 the tooth 28 is allowed to drop into the nearest recess 29, which rigidly couples the wrist and the hand, and the fingers can then again be actuated by the movements of the stump as above described. 90

For rotating the hand after the fingers have closed about an object by turning the stump, without having the fingers let go again of the clutched object by inadvertently opening up, the coupling lever 31 is shifted 95 by hand toward the right over the rack segment 33, which brings its depending tooth 32 into engagement with the ratchet teeth thereof. This shift movement of lever 31 causes the following two operations to take 100 place: The dog 34 is swung about the fulcrum 30 toward the toothed segment 20, fast on pivot pin 12, and is forced by its spring 36 into engagement with the teeth thereof, whereby the pivot pin 12 is rigidly coupled to the hand-supporting disk 9; simultaneously, the lock lever 26 is lifted by the coupling lever 31 acting as wedge in passing underneath in operative contact with the down-curved end of the lock lever 26, so 105 that the depending lever tooth 28 will be lifted out of the recess 29 in the wrist member 4, with the result that now the hand, with the fingers in flexed and locked position, is free to be rotated by the stump in the one or the other direction, without possibility of the fingers inadvertently opening again. 110

For reestablishing normal operation, the coupling lever 31 is shifted back off the rack segment 33, which lets the lever tooth 28 down again for intercoupling the hand and the wrist and which disconnects at the same time the dog 34 from the ratchet segment 20, so that the stump will then actuate only the pivot pin 12 for operating the thumb and fingers, as above described. 115

What I claim is:—

1. In an artificial hand, comprising a hand body and thumb and fingers articu- 120

lated thereto, a brachial sleeve, forearm supporting elements on said sleeve, lower arm supporting elements jointed to said forearm supporting elements, an inverted 5 dish-shaped wrist member at the outer ends of said lower arm supporting elements, a cup-shaped member adapted to be secured to the arm stump, a screw bolt extending from said stump cup, a square portion to said bolt 10 and means for rotatably displacing said bolt relatively to said stump cup and for locking it thereto in the desired relative position, said bolt passing through, and being freely guided in, the bottom of said wrist 15 member, means operable by said square bolt portion for simultaneously actuating the thumb and fingers, comprising a forked lever on said bolt, a tri-armed lever secured to the root of the thumb, the one arm of said 20 lever coöoperating with said forked lever and actuating the thumb, the second arm actuating the two rigidly connected first fingers and the third arm actuating the remaining two fingers, and means for locking thumb 25 and fingers in the respective coöperative position for allowing rotation of the hand, or of the stump, relative to the wrist without at the same time also actuating, or interfering with, the thumb and finger mechanisms.

2. In an artificial hand, comprising a hand 30 body and thumb and fingers articulated thereto, the combination of a stump member to be fixed to the underarm stump, a wrist member to be fixed to the upperarm, means extending from said stump member with 35 controlled capability of relative rotation, passing freely through said wrist member and adapted to simultaneously actuate the thumb and the fingers on rotation of said stump member, and means for locking thumb 40 and fingers in the respective coöperating position and for rotating the hand, or the stump, relative to said wrist member without at the same time also actuating, or interfering with, the thumb and finger mechanisms, comprising a hand operable ratchet 45 mechanism operatively interposed between said wrist member and said hand body, a lock lever controllable by said ratchet mechanism and, if required, also by hand, for 50 normally locking said wrist member and said hand body, and said ratchet mechanism in the operative position adapted to positively control said thumb and finger mechanisms. 55

In witness whereof I have hereunto set my name.

KARL FELIX ROHRMANN.
